UNITED STATES PATENT OFFICE.

SAMUEL T. WHITE, OF DAVENPORT, IOWA.

MECHANICAL MOVEMENT FOR LAUNDRY-WRINGERS.

1,132,815.

Specification of Letters Patent.

Patented Mar. 23, 1915.

Original application filed June 20, 1913, Serial No. 774,747. Divided and this application filed December 12, 1913. Serial No. 806,165.

To all whom it may concern:

Be it known that I, SAMUEL T. WHITE, a citizen of the United States, residing at Davenport, in the county of Scott and State 5 of Iowa, have invented new and useful Improvements in Mechanical Movements for Laundry-Wringers, of which the following is a full, clear, and exact description.

My invention relates to mechanical movements particularly adapted to laundry apparatus, and more particularly to the wringer actuating mechanism of domestic washing machines in which the wringer is driven from the same source of power that drives 15 the washer.

The principal object of my invention is to provide simple and effective mechanism that will drive the wringer in one direction or the other simply by shifting a connecting 20 lever.

Another object of said invention is to enable the operator to release the driving mechanism from the washer by suitable means that may be manipulated by him, 25 either in front or in the rear of the machine, to shift said driving mechanism so that it will operate the wringer mechanism and revolve the same in whichever direction it is desired to have the roller turn.

These and other objects I accomplish by the means and in the manner hereinafter fully described and as more particularly pointed out in the claims, reference being had to the accompanying drawings forming 35 a part of this specification, in which—

Figure 1 is an end elevation of my improved mechanical movement, showing the same applied to the frame of a cylinder washing machine. Fig. 2 is a side elevation 40 of the end portion of the machine to which my improvements are applied. Fig. 3 is a horizontal section taken on line 3—3, Fig. 1 of the end of the machine to which my improvements are applied. Fig. 4 is a horizontal section of said end portion of the machine taken on line 4—4, Fig. 1. Fig. 5 is an enlarged detail view of one of the elements used in shifting the wringer actuating gears. Fig. 6 is an enlarged detail view

showing the wringer driving gears in one 50 position in full lines, and in a reversing position in dotted lines. Fig. 7 is an enlarged detail view of a modified arrangement of the gearing employed in my improved mechanism.

The supporting frame-work of my improved mechanism is so constructed as to support the cylindrical casing C within which the horizontally disposed rotary reciprocable cylinder A is inclosed, and so as 60 to support the actuating mechanism therefor that is situated at one end of the machine. This frame-work includes corner-posts or legs B' that are, preferably, mounted on suitable casters to enable the machine 65 to be rolled with ease, and with suitable longitudinal rails B² connecting said legs near their lower ends, and suitable cross-bars connecting said rails near their ends, and it is so constructed as to provide a platform 70 upon which the motor 1 and gearing are mounted for transmitting the motion to the actuating mechanism. This supporting-frame of the machine also includes a rectangular frame secured to the upper end of 75 the legs, to which the casing C is immediately attached, and the end piece C' of this rectangular frame, at one end of the machine, is connected with a cross-bar B³ by a metallic standard B.

The mechanism for actuating this cylinder A is fully disclosed in and forms the subject-matter of an application for Letters Patent of the United States filed by me June 20, 1913, Serial No. 774,747, for improvements in mechanical movements for washing machines, of which this application is a division, and, therefore, need not be described in detail herein. Suffice it to state, however, that this actuating mechanism comprises a vertically disposed longitudinally reciprocable rack 14 that engages a pinion 15 on the outer extended end of the journal a of said cylinder, which rack is slidably mounted in a vertical casing or 80 guide-frame 13 that is pivoted at its lower end on the standard B. Rack 14 is moved up and down by means of a pitman 17 the

lower end of which is pivoted upon the crank-pin 18 of a large gear 10, which latter is actuated by a pinion 9 on the outer end of a spindle 7. A large gear 6 is secured to the inner end of spindle 7 and is engaged by a pinion 5 fast on the outer end of a suitable shaft that is driven through the medium of a pulley 2 that is connected by a strap or belt 3 to the motor 1. Whenever it is desired to disengage rack 14 from pinion 15 one or the other of horizontally disposed levers 19 and 20 is depressed, and, through the medium of links 22 and 23, will move the casing or frame 13 laterally on its pivot sufficiently to disengage the parts mentioned.

Washing machines of the character to which my improvements are applied, as well as other types of laundry apparatus, require the use of wringer mechanism in connection therewith and are not considered complete without the same. For this reason, it is necessary to provide such wringer mechanism and means for actuating the same so that the rollers thereof can be moved either in one direction or the other, or can be thrown out of engagement with the actuating mechanism of the machine entirely, accordingly as desired. In order to accomplish this result (which is one of the objects of my invention), I mount upon a horizontally disposed shaft 24, substantially parallel with the shaft of pulley 2, a small pinion 25, and on the outer extended end of said shaft a bevel or miter gear 26 is mounted that meshes with a beveled gear 27 and is at substantially right angles thereto. This miter gear 27 is fast on the lower end of a vertically disposed drive-shaft 28 for actuating the wringer 29 mounted on the upper edge of the end piece of frame C'. In order to accomplish this the upper end of shaft 28 is provided with a miter gear 30, and the latter meshes with a miter gear 31 mounted on the extended end of the shaft of the drive-roller 32 of the wringer 29. Gears 30 and 31 are, preferably, surrounded and protected by a hemi-spherical shell or casing 33 having bearings 34 and 35 for both shafts 32 and 28, as shown.

Between gear 25 and beveled pinion 26, shaft 24 has a substantially triangular shaped bracket 37 pivoted thereon which is provided with two inwardly projecting studs 38 and 39 on which suitable gears 40 and 41 are mounted that mesh with each other. When pivotal bracket 37 is moved downward sufficiently, gear 41 will mesh with a drive-pinion 8 mounted on spindle 7 between gears 9 and 6, and through the medium of gear 40 transmits motion to the pinion 25. When this bracket is raised sufficiently, gear 40 will come into mesh with drive-gear 8 and will directly drive the pin-

ion 25 in a reverse direction. In order to facilitate the changing of these gears and reverse the motion of the wringer mechanism, I provide a vertically disposed rod 42 which at its lower end is pivotally connected to bracket 37, and at its upper end is pivotally connected to the outer end of an arm 43 secured to a horizontally disposed rock-shaft 44. This rock-shaft is mounted in bearings 45 secured to and projecting from the ends of frame C', and where said shaft extends beyond these bearings, it is provided with suitable vertically disposed handles or levers 46, the turning of which in one direction or the other rocks shaft 44, so as to raise or lower rod 42 and swing bracket 37 and cause gear 40 or 41 to engage gear 8. When at the limit of its raised or lowered position, the arm 43, to the outer end of which rod 42 is pivoted, will be on a "dead center," as shown in dotted lines in Fig. 9 of the drawings, and when said bracket is in a horizontal position, as shown in full lines in said figure, the gear will be disengaged.

Fig. 7 of the drawings shows a slightly modified arrangement of the gearing employed to reverse the wringer, in which the shifting of a single gear is used instead of two gears. This modification comprises a pulley 50 corresponding to pulley 2 in the preferred form, and gears 51 and 52 corresponding, respectively, to gears 6 and 10 in the preferred form. A pinion 53 is mounted on the end of the pulley-shaft and pinions 54 and 55 are secured to the outer end of the spindle 56. Pinion 53 derives its motion from said pulley-shaft and drives the large gear 51 mounted on one end of spindle 56, which latter, through the medium of pinion 54 on its opposite end, transmits motion to said large gear 52. Pinion 55 is, preferably, in mesh with and drives a pair of idle pinions 58 and 59 that are mounted upon suitable spindles secured to and projecting laterally from the adjacent portion of the platform or cross-bar 60 of the supporting frame of the machine. Pinions 55 and 59 are arranged with their axes in substantially the same vertical plane, while the axis of pinion 58 is slightly to one side thereof. Located immediately above and with its axis in substantially the same vertical plane with pinion 58 is a supplemental pinion 61, that meshes with and derives its motion from pinion 59. All the pinions just mentioned, (i. e. 55, 58, 59 and 61) are of substantially the same diameter and pitch, and are so arranged that their axes substantially form four corners of an imaginary hexagonal figure.

Mounted on the outer end of a longitudinally disposed shaft 62 is a beveled pinion (not shown) that corresponds to the beveled pinion 26 in the preferred form, through the

medium of which the wringer is driven, and adjacent thereto a pinion 63 is mounted on said shaft. Between gear 62 and said omitted beveled pinion, shaft 62 has a suitable elongated bracket 64 pivoted thereon which is provided with a laterally projecting stud 65 on which a shiftable gear 66 is mounted in mesh with pinion 63. When this bracket is moved upwardly or downwardly

- 10 sufficiently, the gear 66 will be brought into mesh with either pinion 61 or pinion 58, according to the direction in which it moves, and through the medium of pinion 63 will drive the wringer mechanism either forward
15 or reversed, as the case may be. Bracket 64 of this modification is moved by a rod 67, similar in construction and operation to rod 42 of the preferred form.

What I claim as new is:

- 20 1. A mechanical movement comprising a horizontally disposed transverse driven shaft, a suitable support for the bearings thereof, a vertical shaft extending downward below the plane of said driven-shaft,
25 miter-gearing connecting the adjacent ends of said shafts, a horizontal shaft disposed at right angles to said driven-shaft, miter-gears connecting the lower end of said vertical shaft and said last mentioned horizontal
30 shaft, a vibratory bracket pivotally mounted on the latter, transmission gearing carried by said bracket that imparts motion to the shaft on which the bracket is mounted, gearing connecting said transmission gearing to
35 the first mentioned driven shaft, a drive-shaft whose bearings are stationary and the axis of which is parallel to said transmission gearing, and means actuated by said drive-shaft that are adapted to be engaged
40 and disengaged by said transmission gearing.

2. A mechanical movement comprising a horizontally disposed transverse driven-shaft, a suitable support for the bearings thereof, a vertical shaft extending downward below the plane of said driven-shaft, miter-gearing connecting the adjacent ends of said shafts, a horizontal shaft disposed at right angles to said driven-shaft miter gears

- Right angles to said driven-shaft, miter-gears
50 connecting the lower end of said vertical
shaft and said last mentioned horizontal
shaft, a vibratory bracket pivotally mounted
on the latter, differential transmission gear-
ing carried by said bracket that imparts mo-
55 tion to the shaft on which the bracket is
mounted, gearing connecting said transmis-
sion gearing to the first mentioned driven
shaft, a drive-shaft whose bearings are sta-
tionary and the axis of which is parallel to
60 said transmission gearing, and means actuated
by said drive-shaft that are adapted to
be engaged and disengaged by said transmis-
sion gearing.

3. A mechanical movement comprising a

horizontally disposed transverse driven-shaft, a suitable support for the bearings thereof, a vertical shaft extending downward below the plane of said driven-shaft, miter-gearing connecting the adjacent ends of said shafts, a horizontal shaft disposed at 70° right angles to said driven-shaft, miter-gears connecting the lower end of said vertical shaft and said last mentioned horizontal shaft, a vibratory bracket pivotally mounted on the latter, transmission gearing carried 75 by said bracket that imparts motion to the shaft on which the bracket is mounted, gearing connecting said transmission gearing to the first mentioned driven shaft, a drive-shaft whose bearings are stationary and the 80 axis of which is parallel to said transmission gearing, and speed reducing gearing having stationary bearings actuated by said drive-shaft that is adapted to be engaged and disengaged by said transmission gearing. 85

4. A mechanical movement comprising a horizontally disposed transverse driven-shaft, a suitable support for the bearings thereof, a vertical shaft extending downward below the plane of said driven-shaft, 90 miter-gearing connecting the adjacent ends of said shafts, a horizontal shaft disposed at right angles to said driven-shaft, miter-gears connected the lower end of said vertical shaft and said last mentioned horizontal 95 shaft, a vibratory bracket pivotally mounted on the latter, transmission gearing carried by said bracket that imparts motion to the shaft on which the bracket is mounted, gearing connecting said transmission gearing 100 to the first mentioned driven shaft, a drive-shaft whose bearings are stationary and the axis of which is parallel to said transmission gearing, means actuated by said drive-shaft that are adapted to be engaged and disengaged by said transmission 105 gearing, a horizontally disposed transverse rock-shaft having stationary bearings above the plane of the lower end of the vertical shaft, a suitable arm projecting therefrom 110 and a rod connecting said arm and said bracket.

shaft, a drive-shaft whose bearings are stationary and the axis of which is parallel to said transmission gearing, speed reducing gearing having stationary bearings actuated by said drive-shaft that are adapted to be engaged and disengaged by said transmission gearing, a horizontally disposed transverse rock-shaft having stationary bearings above the plane of the lower end of the ver-

tical shaft, a suitable arm projecting therefrom and a rod connecting said arm and said bracket. ¹⁰

In witness whereof I have hereunto set my hand this 29th day of November, 1913.

SAMUEL T. WHITE.
